[57] CLAIM

The ornamental design for a razor, substantially as shown and described.

DESCRIPTION

FIG. 1 is a side elevational view of a razor showing my new design, the opposite side being substantially a mirror image thereof;
FIG. 2 is a front elevational view thereof;
FIG. 3 is a back elevational view thereof;
FIG. 4 is a top plan view thereof; and
FIG. 5 is a bottom view thereof.
